UNITED STATES PATENT OFFICE.

RUSSELL ABNER FRISBIE, OF MIDDLETOWN, CONNECTICUT, ASSIGNOR TO THE FRISBIE MOTOR COMPANY, OF MIDDLETOWN, CONNECTICUT, A CORPORATION.

INTERNAL-COMBUSTION ENGINE.

1,252,796.

Specification of Letters Patent.

Patented Jan. 8, 1918.

Application filed October 18, 1916. Serial No. 126,416.

To all whom it may concern:

Be it known that I, RUSSELL ABNER FRISBIE, a citizen of the United States, residing at Middletown, in the county of Middlesex and State of Connecticut, have invented certain new and useful Improvements in Internal-Combustion Engines, of which the following is a specification.

My invention relates to improvements in internal-combustion engines, and the object of my improvement is to produce an internal-combustion engine that is adapted to operate either with gasoline or kerosene, and which is so constructed that both kinds of fuel can be employed simultaneously and in which there is interaction of the different elements of the apparatus that coöperate to provide a maximum of flexibility of the engine structure as a whole.

20 In the accompanying drawings:—

Figure 1 is a front elevation of my improved internal-combustion engine.

Fig. 2 is a rear elevation of the same.

Fig. 3 is a side elevation of the same.

25 Fig. 4 is a view partly in section and partly in side elevation of the trap.

Fig. 5 is a longitudinal sectional view of the converter.

30 My improved internal-combustion engine comprises a set of vertical cylinders 10 mounted on a suitable base 11 in which is operatively housed the crank shaft 12, the same being provided with valve operating mechanism of ordinary form, the valves being housed in the cylinder heads.

The inlet header or manifold 15 extends along the front side of the heads and the discharge header 16 along the rear sides thereof.

40 On the front side of the base 11 is a carbureter 17 for gasoline and a gasoline supply conductor 37 extends upwardly from the gasoline carbureter 17 and is connected at the upper end to the inlet manifold 15 through a trap 38, positioned at one end of the said manifold 15.

The operative mechanism for controlling the operation by gasoline comprises a valve of ordinary form housed in the carbureter 50 17, mounted on a shaft that projects through

the casing as usual, and on which shaft is mounted the carbureter lever 19. A set of levers and connecting rods serves to operatively connect the carbureter lever 19 with the control device at the inner end of the 55 engine, to be described.

The said control device comprises a sleeve 21 formed of tubing, of appreciable length, 60 rotatively and slidably mounted in bearings 22.

The lower end of the sleeve 21 is connected to the set of levers mentioned that connects with the gasoline carbureter 17.

At the upper end of the sleeve 21 is a radial arm 23 that engages with the underside 65 of a sector 24 fixedly supported from the engine structure and having a series of notches for engaging with the arm 23 and locking the same in whatever position to which it may be set.

Axially positioned within the sleeve 21 and extending through the same is a rod 25 that serves as the control for the kerosene operation. The upper end of the rod 25 extends above the sector 24 and a radial arm 70 26 secured to the said upper end extends over the said sector 24, suitably to engage with the upper edge thereof, the latter being also notched, similarly to the lower edge as described.

The lower end of the rod 25 extends an appreciable distance below the lower end of the tube 21 and is connected by a set of suitable interconnecting levers with the kerosene carbureter 29 on the rear side of the 85 engine, near the base 11.

The sets of levers mentioned comprise a radial arm 30 on the lower end of the sleeve 21 and a radial arm 31 at the lower end of the rod 25. A spring 32 is mounted on the lower 90 end portion of the rod 25 and is in bearing engagement by its ends with the radial arms 30 and 31, tending to pull the rod through the sleeve, and thereby holds the control arms 23 and 26 in resilient engagement with the sector 24.

Turning the sleeve 21 or rod 25 accordingly involves a slight longitudinal movement in each case, in opposition to the spring 32, in order to permit the control arms 23 100

and 26 to ride over the notches or teeth of the sector 24.

The inlet manifold 15 and the exhaust header 16 are as described at the upper end 5 portion of the cylinders 10.

Connected to one end of the exhaust header 16 is a converter 33, which extends radially downwardly, the exhaust proper 34 being at the lower end thereof.

10 The said converter 33 is of the type shown and described in the patent granted to me March 21, 1914, No. 1,091,501, and comprises separate passages for the exhaust and the kerosene fuel supply. The exhaust inlet is at the upper end of the converter 33 and the outlet 34 at the lower end thereof. The kerosene inlet is at one side, being connected by a lateral connection 35 with the kerosene carbureter 29 and a second lateral 20 connection 36 connects with the trap 38, and structurally is integral with the latter.

The said trap 38 fits by one end over the end of the supply manifold 15, and the other end is adapted to receive the connection 37 leading from the gasoline carbureter 17, the said trap 38 having openings 40 in the end walls that are in alignment with the inlet manifold 15. The body portion intermediate the said ends is in the interior in 30 the form of an annular channel 39 of about the same diameter as that of the manifold 15 to which it is connected, and the connection 36 that leads from the converter 33 to the trap 38 is connected to the lower side 35 of the said annular channel 39 and extends radially downwardly to the converter 33.

Thus the trap 38 serves to collect any unvaporized fuel, whether gasoline or kerosene, and delivers the same to the converter 40 33. The converter 33 is heated by the exhaust, so that any liquid fuel that is delivered thereto will be vaporized and delivered to the inlet header 15.

As described, complete operative means 45 are provided for operating either with gasoline alone, or kerosene alone, and these means are so related that both kinds of fuel can be used simultaneously because the control devices, comprising the control lever 50 and interconnected mechanism, including a carbureter for each kind of fuel, are independent of those for the other kind, and both sets of control devices can be set to the operating position at the same time, and the 55 quantity of fuel of each kind to be delivered is under complete control.

Furthermore, such mechanism comprises a converter that has the exhaust passage that serves as the fuel heating chamber connected to receive and be heated by the exhaust at all times without change, whether operated by gasoline or kerosene, the fuel passage therein being connected to the kerosene fuel supply on one side and to the trap 65 on the other side.

Thus the converter serves as a re-heater for vaporizing any and all condensation, whether gasoline or kerosene.

The trap 38 comprises at the upper end the trap proper, and at the lower end has an 70 integral conduit 41 that is suitably curved and of proper length to connect with the kerosene outlet connection 36 of the converter 33.

The said trap proper is provided with the 75 annular channel 39 inclosed between the annular end walls 42, which walls have the holes 40 in alignment as described.

The converter 33 is a generally cylindrical double-walled structure, comprising the exhaust chamber 44 extending axially the full length thereof, the upper end having a laterally and inwardly directed flange connection 45 for connecting with the exhaust header 16 and at the lower end there is a 80 second laterally and outwardly directed flange connection that serves as the exhaust outlet 34.

Exterior to the exhaust chamber 44 is the kerosene fuel chamber 46, which is connected 90 at the lower end by means of the port 47 with the lateral connection 35 leading from the kerosene carbureter 29, and adjacent the upper end has an opening 48, indicated by broken lines in Fig. 5, that opens into the 95 lateral connection 36 that leads to the trap 38.

Between the kerosene inlet 47 and outlet 48 the fuel chamber 46 is provided with a system of bridges or baffle plates 49 of interrupted annular form, positioned individually in radial planes, and relatively in staggered relation, being alternatively on opposite sides of the axis, all as described in the 100 patent mentioned.

As described, the exhaust chamber 44 and fuel chamber 46 are arranged so that they cooperate one with the other, the heat from the exhaust serving to heat the fuel as it passes through the fuel chamber.

The preferred method of operation is to start with gasoline and to operate for ordinary running with kerosene, and to use both fuels for forced operation.

The apparatus described permits of this 115 being done, and permits of the change being made from gasoline to kerosene without interruption of the gasoline, the kerosene being gradually turned on as the gasoline is turned off. Furthermore the preliminary 120 operation with gasoline serves to heat the converter so that the engine is ready for proper operation with kerosene without other special heating for kerosene operation.

As an operative feature, when operating 125 with kerosene, it is desirable to admit a relatively small amount of fresh air at normal temperature at the outlet end of the converter, corresponding to the position of the trap. The construction and arrangement 130

described permits this being done by an adjustment such that the gasoline valve is incompletely shut off. Thus air can be drawn through the gasoline carbureter. Some 5 gasoline will be mixed with this air, which feature is merely incidental, and does not involve any disadvantage.

I claim as my invention:—

1. An internal-combustion engine comprising a set of cylinders provided with an inlet manifold and an exhaust header, a carbureter connected to the said manifold, a second carbureter, and a converter, the said converter having an exhaust chamber connected to the said header and a fuel chamber connected between the said second carbureter and the said manifold, and a trap 15 serving as the connecting means for the said

first carbureter and the said converter with the said manifold. 20

2. An internal-combustion engine comprising a set of cylinders having an inlet manifold and an exhaust header, a double chambered converter having one chamber connected to the said header, a trap having 25 an annular body portion, connected by one end to the said manifold, and having an opening at the other end suitable for a fuel inlet, and the said trap having a branch extending laterally from the said body portion, and connected to the other chamber of the said converter. 30
